UNITED STATES PATENT OFFICE.

FREDERICK FIORE, OF BROOKLYN, NEW YORK.

SANITARY TOOTHPICK DISPENSER.

Application filed May 22, 1924. Serial No. 715,108.

To all whom it may concern:

Be it known that I, FREDERICK FIORE, a subject of the King of Italy (who has declared his intention to become a citizen of the 5 United States), residing in the borough of Brooklyn, county of Kings, State of New York, have invented a certain new and useful Sanitary Toothpick Dispenser, of which the following is a specification.

This invention relates to dispensers for toothpicks and the like, and particularly to a device of this character adapted to be manually operated to dispense one toothpick at a time and to present the same in 10 position for withdrawal, and which is sanitary in character.

Dispensers of this type have heretofore possessed the defect that the receptacles containing the toothpicks are more or less unsanitary, in that they are generally provided with an opening, usually at the top of the receptacle, through which the toothpick is adapted to be passed. This opening presents a source of danger to the health of the user 25 of a toothpick from such receptacles because dust, dirt and germs have access to the toothpicks in the receptacle, through said opening, and this is particularly the case with toothpick dispensers located in public places, 30 such as the tables or counters of restaurants and eating places. Another defect possessed by toothpick dispensers heretofore used is that the toothpick delivered from the receptacle is not securely held in position for delivery and both hands of the user are required to prevent the toothpick from falling 35 on to the table or floor.

The primary object of the present invention is to enable a toothpick dispenser to be 40 entirely sanitary in character, the receptacle adapted to contain the supply of toothpicks being closed at all times except when a toothpick is being passed out of the receptacle.

A further object is to cause the toothpick 45 to be securely held in position for delivery above the receptacle while the sanitary closure or cover is closed so that the toothpick may be removed by the same hand of the user which is employed in operating the dispenser.

A still further object is to generally simplify and improve the construction of the 50 dispenser and render it more efficient in operation, as well as cheapening its cost of manufacture.

Still further objects will hereinafter ap-

pear, and to all these ends I have devised the toothpick dispenser described in the following specification and illustrated in the accompanying drawings, forming a part here- 60 of, wherein—

Figure 1 is a front elevation of one preferred embodiment of the dispenser;

Figure 2, a top plan view of the same;

Figure 3, a sectional view, partly in elevation, taken on the line 3—3 of Figure 1;

Figure 4, a side elevation of one end of the receptacle;

Figure 5, a transverse sectional view taken on the line 5—5 of Figure 1, looking in the 70 direction of the arrows;

Figure 6, a longitudinal sectional view through the upper portion of the receptacle, showing a toothpick approaching the final portion of its delivery movement; 75

Figure 7, an enlarged detail sectional view illustrating the toothpick in the position assumed at the completion of the delivery operation;

Figure 8, a top plan view of the receptacle 80 illustrating a modified form of sanitary closure therefor;

Figure 9, a sectional view taken on the line 9—9 of Figure 8, looking in the direction of the arrows, illustrating the operation 85 of the modified form of closure shown in Figure 8; and

Figure 10 is a detail view of a portion of the receptacle illustrating a preferred form 90 of spring jaw construction for holding the toothpick in delivery position.

In the drawings I have shown the toothpick dispenser as forming part of a condiment stand 1, but it is understood that the dispenser may be independently mounted 95 upon any suitable base or may form part of any other desired device. In this instance the top 2 of the condiment stand body may be considered the base. A suitable receptacle 3 is adapted to be mounted above the 100 base 2. This receptacle 3 may be of any desired shape and is here shown as cylindrical in form, of a length slightly greater than that of the toothpicks to be contained therein and of a diameter sufficient to contain any 105 desired quantity of toothpicks. The receptacle may be constructed of metal, glass, or other material, and in this instance I have constructed the same of metal with a removable supply door 4 at one end, adapted to be 110 withdrawn by means of the projecting lip 5, and having at the opposite end an opening 6

covered with transparent material 7 through which the supply of toothpicks within the receptacle is visible.

The bottom of the receptacle in this instance is shown to be provided with a downturned rib 8, and to this rib 8, substantially at the centre thereof, is secured a hollow plunger 9 adapted to reciprocate in a cylinder 10 located below the base 2. The plunger 9 and cylinder 10 are adapted to house a suitable resilient member, here shown as a coiled spring 11, which tends to urge the receptacle to its upward position above the base 2. Rigidly secured to the base 2 are a plurality of standards 12 and 13. The upper portions of these standards 12 and 13 are adapted to pass through openings 14 in the rib 8 and the upper ends of the standards are substantially flush with the bottom 20 of the receptacle 3. These upper ends of the standards have projecting portions 15 adapted to bear against the bottom of the receptacle above the openings 14, thus fixing the upward limit of travel of the receptacle against the coiled spring 10.

The upper ends of the standards 12 and 13 preferably have aligned grooves 16 and 17 of sufficient width to accommodate but one toothpick, and the standards are so spaced that at one end, in this instance the end adjacent to the standard 12, the toothpick resting in the grooves 16 and 17 will project a short distance therebeyond, as indicated at 18.

The receptacle has a suitable manually operated lever 19, which, upon being pressed down causes the receptacle to descend toward the base 2, guided by the standards 12 and 13. This movement brings the top of the receptacle down toward the upper ends of the standards 12 and 13, so that the toothpick resting in the aligned grooves 16 and 17 is positioned adjacent to the top of the receptacle. The descending movement of the receptacle causes all the other toothpicks therein to fall away from above the upper ends of the standards so that there is no congestion at the top of the receptacle.

Toward the latter part of the downward movement of the receptacle the end 18 of the toothpick to be delivered is caused to be engaged by a transverse pin or bar 20, seen clearly in Figure 6, and the adjustment is such that the pin 20 is adapted to move past the edge 21 of the groove 16 and this movement causes the toothpick to be tilted, the edge 21 acting as a fulcrum, so that the toothpick is turned from a horizontal to a vertical position. A further portion of the downward movement of the receptacle causes the standard 12 to wedge the toothpick between small spring jaws 22, preferably located at a small V-shaped opening or delivery aperture 23 forming part of the longitudinal opening 24 in the top of the receptacle, so that the toothpick is securely held in a vertical position as seen in Figure 7, ready for withdrawal.

As seen in Figure 10, the small spring jaws for holding the toothpick in delivery position may be constructed as seen at 40 in this figure, whereby the jaws are adapted to be located within the V-shaped opening 23 without projecting into the receptacle. This construction enables the receptacle to be moved relatively to the base so that the groove 16 of the standard 12 is substantially in alignment with the V-shaped opening 23 and the toothpick projected from the receptacle is thereby adapted to be more firmly wedged within the jaw members.

The sanitary closure which I have provided for the toothpick receptacle will now be described. As seen in the drawings, the top of the receptacle 3 is provided with a longitudinal opening 24, of which the opening 23 already referred to forms a part. This opening 24 is adapted to be covered by a suitable closure door 25, shown in Figures 1, 2, 3, and 6. The door 24 preferably conforms to the outer configuration of the receptacle 3, and is held closed by a small spring 26 of relatively slight flexibility. During the passage of the toothpick from the receptacle the end 27 of the toothpick is caused to engage the inner surface of the closure door 25, as seen in Figure 6, and as the toothpick moves out of the receptacle toward the vertical position under the influence of the pin 20, the toothpick slides past the door and the door 25 is caused to open upon its hinge 28. When the toothpick has passed the end 29 of the door 25 the door will snap closed behind the toothpick to its normal closed position, under the influence of the spring 26, the toothpick at this time being held between the small spring jaws 22, as seen in Figure 7.

Upon the removal of pressure from the manual lever 19 the coiled spring 11 causes the receptacle to rise to its normal upward position, carrying with it the toothpick in vertical delivery position. The toothpick is then adapted to be removed by the same hand of the user with which the lever 19 has been manipulated. The device operates rapidly, the user simply pressing the lever with one or more fingers and removing the toothpicks desired, one at a time. The enclosed receptacle maintains the toothpicks in a clean and sanitary condition. The device is simple in appearance, construction and operation, but may be made as ornamental as desired for use in homes, as a buffet accessory, as well as in public eating places.

The means shown herein for mounting the receptacle upon the base 1, comprising the downturned rib 8, plunger 9 and standards 12 and 13, represent but one embodiment of this construction. A plurality of plungers

may be provided for imparting greater stability; or the plunger 9 may be omitted entirely and the standards 12 and 13 suitably equipped with resilient means for urging the receptacle to its normal position. Similarly, any number of standards may be employed and the same are capable of variations in construction; except that they are intended to be located on the base and adapted to project into the receptacle in a manner to receive a toothpick to be ejected from the receptacle and to cooperate with the stop 20. The stop 20 is here shown as a pin or bar, but a mechanical equivalent may be substituted without departing from this invention.

Referring particularly to the modification illustrated in Figures 8 and 9, I have illustrated a sanitary closure door of double construction, adapted to operate with somewhat greater facility than the single door construction already described. In this instance the closure consists of two members 30 and 31, hinged at 32 and 33, respectively and having resilient members or flexible spring members, indicated at 34 and 35, respectively. The ends 36 and 37 of the closure members 30 and 31 are adapted to meet at a point substantially in alignment with the spring jaws 23. In this case, the toothpick, in passing out of the receptacle, slides past the meeting ends 36 and 37, thus eliminating to a considerable extent the resistance imparted by the closure, and contributing to the refinement of the construction.

It is understood that various changes might be resorted to in the construction, form and arrangement of the several parts without departing from the spirit and scope 40 of my invention, hence I do not wish to be limited strictly to the constructions herein shown and described.

What I claim is:

1. A sanitary toothpick dispenser comprising a receptacle to contain a supply of toothpicks and having an opening to afford egress for a toothpick, means to project a toothpick partly through said opening, means to hold said toothpick in delivery position, and a closure for said opening, said closure normally held closed, said projected toothpick arranged to slide past said closure to open the same for passage of the toothpick, said closure arranged to close behind the toothpick and remain closed while said toothpick is held in delivery position by said holding means.

2. A sanitary toothpick dispenser comprising a receptacle to contain a supply of toothpicks and having an opening to afford egress for a toothpick, means to project a toothpick partly through said opening, a sanitary closure for said opening, said closure arranged to be opened by engagement with said toothpick during the inter-

val of its projection and to close behind the toothpick when the toothpick attains delivery position, and means independent of said closure to hold said toothpick in delivery position.

3. A sanitary toothpick dispenser comprising a receptacle to contain a supply of toothpicks and having an opening to afford egress for a toothpick, means to project a toothpick through said opening, a sanitary closure for said opening and resilient means to normally maintain said closure in closed position, means to hold said toothpick in delivery position, said closure arranged to be opened by engagement with said toothpick during the interval of its projection from the receptacle and said resilient means arranged to return said closure to its normal closed position behind the toothpick when said toothpick is presented to said holding means.

4. A sanitary toothpick dispenser comprising a base, a receptacle adapted to contain a supply of toothpicks and having an opening affording egress for a toothpick, means for effecting projection of a toothpick partially through said opening, a sanitary closure for said opening normally held closed and adapted to be opened by engagement with said toothpick during the interval of its projection from said receptacle, said projecting means being adapted to impart a tilting movement to said toothpick during its egress from said receptacle, said toothpick having sliding engagement with said closure, and means for holding the toothpick in delivery position partially within and partially without said receptacle after said toothpick has passed said closure.

5. A sanitary toothpick dispenser comprising a stationary base, a movable receptacle mounted on said base, said receptacle being adapted to contain a supply of toothpicks and having an opening affording egress for one toothpick at a time, means on said base adapted to project into said receptacle and to receive a toothpick to be ejected therefrom, a sanitary closure for said receptacle, said receptacle being adapted to be moved toward said base whereby a toothpick to be ejected is located in closer proximity to said opening, a stop adapted to cooperate with said toothpick receiving means and to engage one end of said toothpick whereby said toothpick is tilted, and the opposite end of said toothpick engaging said sanitary closure to effect opening thereof affording partial projection of said toothpick from said receptacle, and resilient means for holding said toothpick in delivery position, said sanitary closure arranged to close behind said toothpick and to remain closed while said toothpick is held in said delivery position.

6. A sanitary toothpick dispenser com-

prising a receptacle having an egress opening and a delivery aperture, means to project a toothpick partially through said opening, a spring clip in said delivery aperture 5 to hold said toothpick in delivery position, and a closure for said opening, said closure arranged to open during passage of the toothpick from the receptacle and to close and remain closed while said toothpick is held in delivery position.

7. A sanitary toothpick dispenser comprising a receptacle having a filling opening at one of its ends, a removable supply door for said filling opening, said receptacle 15 also having an egress opening and a V-shaped delivery aperture, means to project a toothpick partially through said egress

opening, a spring clip at said V-shaped delivery aperture to hold said toothpick in delivery position, and a closure for said 20 egress opening, said closure arranged to open during passage of the toothpick from the receptacle and to close and remain closed when said toothpick attains delivery position.

25

8. A sanitary toothpick dispenser as set forth in claim 1, said closure comprising a plurality of members hinged at opposite sides of said egress opening, the meeting portions of said members substantially in 30 alignment with said holding means.

In testimony whereof, I have signed this specification.

FREDERICK FIORE.
